UNITED STATES PATENT OFFICE.

CHARLES V. ANTHENAT, OF SHERIDAN, ILLINOIS.

AUTO-HEATER.

1,205,420.

Specification of Letters Patent. Patented Nov. 21, 1916.

Application filed March 23, 1916. Serial No. 86,166.

To all whom it may concern:

Be it known that I, CHARLES V. ANTHENAT, a citizen of the United States, residing at Sheridan, in the county of La Salle, State 5 of Illinois, have invented certain new and useful Improvements in Auto-Heaters; and I do hereby declare the following to be a full, clear, and exact description of the invention, such as will enable others skilled 10 in the art to which it appertains to make and use the same.

This invention relates to heating devices, and is adapted particularly for use in connection with motor vehicles.

15 The primary object of the invention is to provide a simple and efficient means for directing heat units to the interior of the motor vehicle, whereby the occupants of the vehicle may be made warm and comfortable 20 during cold weather.

A further object of the invention is to provide a device of the character described which utilizes the heat radiating from the motor and exhaust pipe.

25 A still further object of the invention is to provide a device of this character which is capable of being operated to heat the car when desired, and which may be entirely closed if need be, to prevent the admission 30 of heat to the vehicle body.

With these objects in view, together with others which will appear as the description proceeds, the invention resides in the novel combination and arrangement of parts, all 35 as will be described more fully hereinafter, illustrated in the drawings and particularly pointed out in the claims.

The invention will be best understood by reference to the accompanying drawings, 40 wherein:

Figure 1, is a longitudinal sectional view through a portion of a motor vehicle and illustrating the application of a heating device embodying my invention. Fig. 2 is a 45 sectional view taken on line 3—3 of Fig. 1. Fig. 3, is a detail perspective view of the radiator plate removed from the vehicle and illustrating the same in closed position, and Fig. 4, is a perspective view of the damper 50 plate for the heater.

Referring now more particularly to the drawings, the vehicle motor is indicated generally at 5, and is provided with the usual exhaust pipe communicating with the 55 various cylinders of the motor and extending rearwardly therefrom beneath the floor

7 of the vehicle to the muffler (not shown) at the rear of the vehicle.

Arranged upon the inclined forward portion of the floor 7, and preferably in close proximity to the dash of the vehicle body is a radiator plate 9. This plate is rectangular in shape and may be formed of thin metal, the said plate being positioned directly over the exhaust pipe of the vehicle 60 motor. The radiator plate has a centrally depressed portion, the juncture of the lateral edges of the depressed portion with the side portions of the plate forming spaced parallel shoulders 10. This depressed portion is provided with a plurality of elongated slots constituting ports or apertures through which heat beneath the vehicle floor may pass into the vehicle body. A substantially narrow laterally disposed slot 11 65 is provided in the radiator plate 9 adjacent the rear edge thereof, the said slot being of a length equal to the distance between the shoulders 10 at the edges of the depressed portion. Spaced parallel flanges 12 depend 70 from the under side of the radiator plate 9, the said flanges being spaced apart a distance equal to the length of the slot 11, and each flange is provided with a longitudinally disposed channel or groove 13 communicat- 75 ing at one end with the adjacent end of the slot 11. A damper plate 14 is provided and is adapted to slide within the slot 11 and to engage at its edges within the channels 13 formed in the flange 12. This damper plate 80 85 may be provided at one end with a finger tab 15 to facilitate sliding of the same. The opposite end of the plate is cut away as at 16 to permit of the same engaging over the exhaust pipe beneath the vehicle floor. 90 The forward edges of the depending flanges 12 may be rounded or shaped to correspond with the contour of the rear portion of the engine casing.

A heat collecting member is arranged 100 over the exhaust pipe upon the vehicle motor, the said element consisting of a metallic plate 17 provided along one of its longitudinal edges with suitable apertures through which bolts 18 may be inserted to 105 secure the said plate at one edge to the motor casing, and is bent outwardly and downwardly throughout the remainder of its lateral extent to inclose the rearwardly extending exhaust pipe as shown. The rear 110 end of the plate 17 may be contracted into substantially funnel shape as shown, and

2
directs the heat radiated from the exhaust pipe into the space between the depending flanges 12 on the heat radiator plate 9. It is thus seen that heat will be directed beneath the radiator, and when the damper plate 14 is engaged in the channel 13 the heat will be deflected thereby in an upward direction to pass through the apertures formed in the depressed portion of the radiator plate. When it is desired to discontinue the flow of heat, the damper 14 may be withdrawn from the flanges 12 and laid flat within the depressed portion of the plate 9 with its lateral edges engaged with the shoulders 10 at the juncture of the depressed portion with the edge portions of the radiator plate. It is thus seen that the damper member lies flush with the uppermost surface of the radiator plate, and spring clamp members 19 secured to the lateral edges of the plate 9 hold the damper plate securely within the depressed portion. When in this position, it is apparent that the heat directed by the collecting plate 17 will pass beneath the floor of the vehicle to the rear end thereof, and cannot gain access to the interior of the vehicle. The radiator plate 9 may be secured to the floor of the vehicle by suitable screws or bolts 20.

30 While I have herein shown and described a particular or preferred embodiment of the invention, I desire to have it understood that I need not confine myself to all the precise details of construction herein set forth by way of illustrating as modification and variation may be made without departing from the spirit of the invention or exceeding the scope of the claims.

What is claimed is:

- 40 1. In a device of the class described, the combination with a motor vehicle, of a heat register arranged in the floor of said vehicle over the exhaust pipe of the motor, spaced flanges depending from said register one upon each side of said pipe and being provided with grooves, and a damper plate adapted to slide in said grooves, substantially as described.
2. In a device of the class described, the combination with a motor vehicle, of a heat register including a plate arranged in the floor of said vehicle over the exhaust pipe

of the motor and being provided with openings, spaced flanges depending from said plate one upon each side of said pipe and being provided with grooves, the said plate being provided with a transverse slot communicating at its opposite ends with said grooves, and a damper plate adapted to slide in said grooves, substantially as described.

3. In a device of the class described, the combination with a motor vehicle, of a heat register comprising a plate arranged in the floor of said vehicle over the exhaust pipe of the motor thereof, the said plate having an apertured depressed central portion providing spaced parallel shoulders, flanges depending from said plate and being spaced apart a distance equal to that between said shoulders and positioned one on each side of said exhaust pipe, the said flanges being provided with channels, the said plate having a transverse slot communicating at its ends with said channels, a damper plate adapted to slide through said slot and to engage at its opposite edges in said channels for sliding movement therein, and clamps secured adjacent the edges of said register plate and projecting over said depressed portion, substantially as described.

4. In a device of the class described, the combination with a motor vehicle, of a plate located in the floor of said vehicle behind the engine having centrally disposed apertures, said plate being depressed inwardly from its lateral edges to provide spaced parallel shoulders, and being provided with a transverse slot equal in length to the distance between said shoulders, flanges extending in spaced relation from the underside of said plate and being connected thereto by said shoulder portions, the said flanges having grooves communicating with the opposite end of said slot, a damper plate adapted to slide in said slot and grooves, and damps on said register plate, substantially as described.

In testimony whereof, I affix my signature, in the presence of two witnesses.

CHARLES V. ANTHENAT.
